UNITED STATES PATENT OFFICE.

RICHARD P. MARTIN, OF HUNTER, OKLAHOMA.

SKID.

1,076,593.

Specification of Letters Patent.

Patented Oct. 21, 1913.

Application filed July 8, 1913. Serial No. 777,930.

To all whom it may concern:

Be it known that I, RICHARD P. MARTIN, a citizen of the United States, residing at Hunter, in the county of Garfield and State 5 of Oklahoma, have invented a new and useful Skid, of which the following is a specification.

This invention relates to an improved form of safety skid for the convenient unloading of barrels from a freight car with the understanding, however, that the device can be applied with equal facility for the transporting of barrels from an upper platform to a lower one.

15 A further object is to provide a safety skid with an apron secured to and adjacent the bottom extremity thereof and which apron is disposed at an angle to the skid whereby the downward velocity of the barrels will be checked and the barrels reaching the lower platform will move substantially tangential thereto.

20 A further object is to provide a safety skid with a head bar extending over the upper platform and with which a barrel initially contacts so as to prevent the skid from being moved away from the platform.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed, can be made within the scope of what is claimed, without departing from the spirit of the invention.

In the drawings accompanying this specification the preferable form of my invention 40 is illustrated, in which:—

Figure 1 is a view in perspective of my improved safety skid. Fig. 2 is a longitudinal sectional view thereof with the apron 45 folded within the safety skid as it will be during the non-use of the same. Fig. 3 is a cross sectional view.

Referring to the drawings in which similar reference numerals designate correspond- 50 ing parts throughout the several views, 4 are the guide rails held in spaced relation by the struts or cross bars 5. The strut bars 5 dip downwardly at their center portion so as not to interfere with the curved portion 55 of a barrel during its transit down the skid.

The guide rails 4 are provided with their

top extremities and the under surfaces of the lower extremities beveled. The inclination of the bevels is such that during the normal use of the skid, the lower bevel will 60 be substantially horizontal while the upper bevel will be downwardly inclined at a slight angle.

Extending along the under surface of each guide rail are the reinforcing strips 6 preferably formed of metal and which extend along the lower bevel and terminate in the downwardly extending claws or prongs 7, the latter being adapted to bite into and engage the lower platform or the ground 70 upon which they rest. A number of screws 8 extend through the reinforcing strips and rigidly secure the same to the guide rails. The upper extremities of the strips are bent as at 9 to engage the head bar 10, after 75 which the strips are bent forwardly along the upper bevel portion as illustrated at 11. The head bar 10 is thus held positioned beyond the uppermost extremity of the side rails and is thus adapted to extend within 80 a car with the result that when a barrel is being positioned upon the skid it is lifted over and on the head bar which prevents the skid from being moved away from the car which thereby renders unnecessary any 85 upper securing means as it is thought will be readily apparent.

Extending between the guide rails adjacent their lower extremities is a shaft 12 upon which is journaled the apron 13. The 90 apron 13 comprises the broad flat outer portion 14 and the restricted portion 15, the latter being curled around or journaled upon the shaft 12 as illustrated at 16. The apron is preferably formed of sheet metal 95 of sufficient thickness to withstand the pressure and blows which will be brought to bear thereupon incident to the sliding of a barrel down the guide rails and contacting with the apron. The apron 13 checks the 100 downward velocity of the barrels and also changes the direction of motion thereof so as to be practically tangential to the lower platform which therefore protects the same against injury. The apron is of limited 105 width so that it may fold between the guide rails as illustrated in Fig. 2. Mention might also be made of the fact that the apron will under certain circumstances contact with the claws 7 to prevent the lateral 110 displacement of the safety skid.

Having thus fully described the invention,

what I claim to be new and original with me is:—

1. A skid comprising guide rails, means extending therebetween and adapted to hold the same in spaced relation, a shaft extending between the guide rails adjacent the lower extremities thereof, an apron journaled upon the said shaft and adapted to rotate about the same as an axis, said apron formed of a sheet of wide flat material and adapted to extend at an angle to the guide rails.

2. A skid comprising spaced guide rails, a reinforcing member extending around the under edge thereof and terminating in downwardly extending claws at the lower extremities of said guide rails, a shaft extending between the guide rails adjacent the lower extremities thereof, and an apron rotatably mounted upon and secured to said shaft, extending at an angle to said guide rails and adapted to fold therebetween during the non-use thereof.

3. A skid comprising guide rails, downwardly curved strut bars extending between said guide rails and adapted to hold the

same in spaced relation, reinforcing strips secured to the under edges of said guide rails and terminating at their lower extremities in downwardly extending claws, a head bar extending between the said guide rails and secured thereto by the said reinforcing strips, said head bar adapted to rest upon an upper platform for the supporting of the skid, a shaft rigidly secured to and extending between the lower extremities of the said guide rails, an apron provided with a curled portion rotatably secured to the said shaft between the said guide rails adapted to guide the movements of the transported articles substantially tangential to the lower surface upon which the skid rests, said apron adapted to fold between the said guide rails during the non-use thereof.

In testimony that I claim the foregoing as my own, I have hereto affixed my signature in the presence of two witnesses.

RICHARD P. MARTIN.
